UNITED STATES PATENT OFFICE.

HENRY F. SCHMIDT, OF PITTSBURG, PENNSYLVANIA, ASSIGNOR TO THE WESTINGHOUSE MACHINE COMPANY, A CORPORATION OF PENNSYLVANIA.

TURBINE.

986,817.

Specification of Letters Patent. Patented Mar. 7, 1911.

Application filed August 18, 1909. Serial No. 513,433.

To all whom it may concern:

Be it known that I, HENRY F. SCHMIDT, a citizen of the United States, and a resident of Pittsburg, in the county of Allegheny and State of Pennsylvania, have made a new and useful Invention in Turbines, of which the following is a specification.

This invention relates to turbines and has for an object to produce a small sized turbine of relatively large capacity.

A further object is to produce means for reversing the direction of the fluid after it has done work in one series of working passages and for delivering it to a second series carried on the same working wheel.

A further object is to produce means for reversing the direction of the motive fluid after it has been delivered from a row of blades and for redirecting it so that it is again delivered to the same row of blades, but to a portion of the blades through which it has not previously passed.

A further object is to produce a blade provided with two radially disposed working portions through which the fluid is adapted to pass in opposite directions.

A further object is to produce reversing and redirecting channels which are simple in construction, easily assembled and effective in operation.

These and other objects I attain by means of an apparatus embodying the features herein described and illustrated.

In the drawings accompanying this application and forming a part thereof: Figure 1 is a fragmental sectional elevation of a turbine embodying my invention; Fig. 2 is a partial section along the line 2-2 of Fig. 1; Fig. 3 is a perspective view of a blade embodying my invention; Fig. 4 is a fragmental view of the turbine wheel provided with blades, embodying my invention; Fig. 5 is a section along the line 5-5 of Fig. 3; Fig. 6 is a plan view of the channel bevels on which a number of channel shrouds are secured; and Figs. 7 and 8 are perspective views of a guide block partition piece which forms a detail of my invention.

The turbine illustrated as embodying my invention is provided with means, such for example as diverging nozzles for initially delivering and directing the motive fluid to the working elements. The fluid delivered by the nozzles, after having traversed a row of working passages formed by the working

elements carried by the turbine wheel, is received by a series of reversing channels and, after being reversed in direction, is delivered to a second row of working passages formed by the same elements.

Although I do not consider it necessary to illustrate the various modifications and arrangements of my invention, it will be understood that the steam may be expanded by additional means after it has been discharged a second time from the working elements and that it may then be delivered to additional wheels or to additional rows of elements carried by the same wheel. The arrangements may also be such that the steam may be delivered to an additional row of working elements without further expansion or it may be expanded after each abstraction of energy and it may be reversed one or more times in traversing the working element carried by one wheel. The features of my invention may also be embodied in a reaction type of turbine, in which the steam is expanded in each row of working pas-

Referring to the drawings by means of the reference numerals: The turbine illustrated includes a casing 7, which is provided with steam inlet and exhaust ports, and a rotor element 8, on which blades 9 are mounted. The inlet port communicates with a passage 10, formed in the casing and which communicates with and delivers steam to one or more diverging or expansion nozzles 11. The nozzles 11 deliver steam to the blades 9.

Each blade 9 is provided with a concave working face 12 and convex face 13, which is provided with transversely extending slots 14 and 15 and which is of such contour that it fits snugly against the concave face of the next adjacent blade when the blades are in place on the turbine wheel. The slots 14 and 15 form steam passages between the blades which render the concave face of each blade effective as working elements, at two points along the blades. Each blade is provided with a mounting portion which may consist of a cylindrical shank 16 adapted to be secured into radially extending openings in the peripheral face of the wheel 8 by means of pins 17 which extend through transversely extending holes 18, provided in the shank 16 of the blade, and which are riveted over at each

side of the wheel 8 to hold the blade securely in place. The body portion of each blade between the slots 14 and 15 is cored out on the convex side of the blade, as at 5 19, for the purpose of reducing the weight of the blade. As this hollowed out portion is covered by the concave face of the next adjacent blade when the blades are in place on the turbine, it does not effect the flow of 10 steam through the turbine.

The nozzles 11 deliver steam to the annular row of passages formed by the coöperation of the slots 14 and the concave faces 15 of the blades. The steam in traversing these passages, imparts a portion of its velocity energy to the blades and is delivered to a series of reversing channels 21, which redirect it and deliver it to the annular row of passages, formed by the coöperation of 20 the slots 15 and the faces 12 of the blades. The steam delivered to the blades by the reversing channels, imparts its available kinetic energy to the blades and is discharged by them into the exhaust passages 25 of the turbine.

In order that the blades may be milled in one operation and that the outlet angles of the working passages formed by the slots 14 may be greater than the inlet angle of 30 the working passages formed by the slots 15, I provide an offset 22 on each blade, the concave face of which is continuous with the concave face of the blade and which may be milled in the same operation with 35 the milling of the face of the blade. The channels 21 are U shaped and are formed by the coöperation of a guide or channel block 23 and guide block partition pieces 24. The channel block 23 is provided with a plurality 40 of substantially crescent shaped depressions, deeper at their inner ends and arranged in stepped relations. The crescent shaped face 45 of each depression is inclined to the lateral face of the wheel 8 and the dividing faces 26 between adjacent depressions are normal to the planes of the faces 25.

The partition pieces 24 coöperate with the normal faces 26 to form the U shaped delivery channel which reverses steam and 50 delivers it to the blade 9. These pieces 24 consist of a flat crescent shaped portion 27 which conforms in shape to the faces 25 of the channel block 23, and a U shaped extension or partition 28 which is beveled off 55 at 29. The crescent shaped portion 27 of each piece is adapted to be secured to one

of the faces 25 of the block 23 by means of a flathead countersunk screw 26¹. The partitions 28 coöperate with the faces 26 of the channel block 23 to form the fluid reversing 60 passages, which receive the fluid delivered from the passages formed by the slots 14 of the blades and deliver it to the passages formed by the slots 15 of the blades. These channels extend substantially radially of 65 the turbine and one or more may be provided for each delivery nozzle 11.

In order that the turbine may operate efficiently and that the channel 21 may efficiently receive and deliver motive fluid, it is essential that the walls of these channels extend into close proximity with the passages formed by the slots 14 and 15 of the blades. Inasmuch as each of the blades 9 is provided with an offset 22, I find it advisable to provide an offset 31 on the channel block 23 so that the upper end of the channels 21 will project into close proximity with the passages formed by the slots 15. The upper arm of the U shaped partition 75 28 of each piece 24 is longer than the lower arm and consequently the beveled edges 29 of the partitions project out farther at the outer side of the channel than at the inner. With this arrangement steam issues from the passages formed by the slots 14 at the proper angle and is delivered at the proper angle to the passages formed by the slots 15.

What I claim is:

1. A turbine blade adapted to receive motive fluid at two points and an offset on said blade for increasing the delivery angle at one point of the blade. 90

2. A turbine blade provided with an offset for increasing the angle of delivery of 95 the blade at one point.

3. A turbine blade provided with fluid delivery passages in its convex face, and an offset at one point to increase the delivery 100 angle of the blade at that point.

4. A turbine blade provided with an offset at one point, and means for rendering the blade effective as a working agent at two points along its length.

In testimony whereof, I have hereunto 105 subscribed my name this 22nd day of July, 1909.

HENRY F. SCHMIDT.
